UNITED STATES PATENT OFFICE.

CHARLES E. MERRIFIELD, OF INDIANAPOLIS, INDIANA.

IMPROVEMENT IN GRAIN-SEPARATORS.

Specification forming part of Letters Patent No. **222,360**, dated December 9, 1879; application filed October 14, 1879.

To all whom it may concern:

Be it known that I, CHARLES E. MERRIFIELD, of Indianapolis, county of Marion, and State of Indiana, have invented a new and useful Improvement in Grain-Separators, of which the following is a description, reference being had to the accompanying drawings.

My invention relates to a new mode of shaking the grain out of the chaff and straw of a separator; and it consists, mainly, of the new construction and arrangement of the shaking devices; also, in the new combination of elements, which are deemed essential in my newly-organized device, as will herein-after be first fully described in the specification, and then set forth in the claims.

In the accompanying drawings, in which like letters of reference in the different figures indicate like parts, Figure 1 represents a perspective view of my improved device. Fig. 2 is a side elevation of the same. Fig. 3 is a vertical section, taken longitudinally through the center; and Fig. 4 is a modified form of the shaking device.

A, A', B, and C represent, respectively, the two sides, top, and bottom of a box in which are mounted four shafts, D, G, I, and D', the ends of each shaft having bearings in the sides A, A'. The shafts D' and G are provided on one end; outside of the side A', with cranks K, K', which are connected together by the connecting-rod L, and operated by the pitman P. It is obvious that the end p of the pitman P must be connected with a crank or eccentric (not shown) for operating the shafts D' and G. Each of the shafts D' and G is provided with a series of vertical arms, H, as shown in Figs. 1 and 3.

One end of each of the flexible straps f is secured to an arm, H, of the shaft D', and the other ends of the straps f are secured to the shaft I. In like manner are the straps a attached to the arms H of the shaft G and to the shaft D. Thus, when the rod P and connecting-rod L are operated, a vibrating motion is imparted to the cranks K, K', also to the shafts D' and G, thus causing the flexible

straps f and a to be alternately loosened and tightened, thus tossing the straw that may be placed thereon and shaking out the grain from the chaff and straw.

The shafts D and G are set lower in the frame than the shafts D' and I, and the straw is tossed from the lower set of straps, a, onto the upper set, f, and from there out of the box.

The shafts D and I may be provided at one end with ratchets D² and I² and pawls m, m', for the purpose of holding said shafts, and at the same time permitting the slack of the flexible straps to be taken up when said straps become too loose.

In Fig. 4 I have represented a modified form of the shaking device, in which D² is a shaft provided with projecting arms H², to which is secured one half of a hinge, v. The other half of said hinge is attached to a strip of wood, o, and the strip o is attached to the strip o' by the hinge u, on top. The outer end of the strip o' passes through the shaft I², as shown. When the shaft D² is operated or vibrated one way the bisected strip o o' drops down at the hinge-joint u, and when the shaft D² is vibrated in the opposite direction the bisected strip o o' assumes the position shown, thus tossing the straw and separating the grain in the same manner as with the flexible strips shown in Figs. 1 and 3.

What I claim as new is—

1. In a shaking-screen for separating grain from chaff and straw, the shaft D', provided with arms H and a crank, K', combined with the flexible straps f and shaft I, as and for the purpose specified.

2. The shaft D', with crank K' and arms H, combined with the flexible straps f and the shaft I, with ratchet I² at one end, and pawl m, as and for the purpose specified.

In testimony whereof I have signed my name to this specification in the presence of two subscribing witnesses.

CHARLES E. MERRIFIELD.
